Primary Examiner — Clare E Heflin(57) **CLAIM**

The ornamental design for a roadway LED luminaire, as shown and described.

DESCRIPTION

FIG. 1 is a top, front perspective view of the roadway LED luminaire showing my new design;

FIG. 2 is a front elevation thereof;

FIG. 3 is a rear elevation thereof;

FIG. 4 is a side elevation thereof;

FIG. 5 is an opposite side elevation view thereof;

FIG. 6 is a top plan view thereof; and,

FIG. 7 is a bottom plan view thereof.

The broken lines shown on the drawings depict portions of the roadway LED luminaire that form no part of the claimed design.
